(57) **CLAIM**

The ornamental design for a light-emitting diode, as shown and described here.

DESCRIPTION

FIG. 1 is a top perspective view of the light-emitting diode showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side view thereof; and,

FIG. 7 is a right side view thereof.
